(57) **CLAIM**

The ornamental design for a door facing therefor, as shown and described.

DESCRIPTION

FIG. 1 is a front perspective view of a first version of the door facing;

FIG. 2 is a front elevational view;

FIG. 3 is a rear elevational view;

FIG. 4 is an enlarged cross-sectional view taken along the line 4-4 of FIG. 1;

FIG. 5 is a top view;

FIG. 6 is a bottom view;

FIG. 7 is a cross-sectional view taken along the line 7-7 of FIG. 2;

FIG. 8 is an enlarged cross-sectional view of the encircled portion of FIG. 7;

FIG. 9 is a right side view;

FIG. 10 is a left side view;

FIG. 11 is a cross-sectional view taken along the line 11-11 of FIG. 2;

FIG. 12 is an enlarged cross-sectional view of the encircled portion of FIG. 11;

FIG. 13 is a front perspective view of a second version of the door facing;

FIG. 14 is a front elevational view;

FIG. 15 is a rear elevational view;

FIG. 16 an enlarged cross-sectional view taken along the line 16-16 of FIG. 13;

FIG. 17 is a top view;

FIG. 18 is a bottom view;

FIG. 19 is a cross-sectional view taken along the line 19-19 of FIG. 14;

FIG. 20 is an enlarged fragmentary cross-sectional view of the encircled portion of FIG. 19;

FIG. 21 is a right side view;

FIG. 22 is a left side view;

FIG. 23 is a cross-sectional view taken along the line 23-23 of FIG. 14;

FIG. 24 is an enlarged cross-sectional view of the encircled portion of FIG. 23;

FIG. 25 is a front perspective view of a third version of the door facing according to the first version of our door design;

FIG. 26 is a front elevational view;

FIG. 27 is a front perspective view of a fourth version of a the door facing;

FIG. 28 is a front elevational view;

FIG. 29 is a front perspective view of a fifth version of a the door facing;

FIG. 30 is a front elevational;

(Continued)

FIG. 31 is a front perspective view of a sixth version of the door facing; and,

FIG. 32 is a front elevational view.

The evenly spaced broken lines depict portions of the door facing that form no part of the claimed design. The dot-dot-dash broken line circles depict the limits of the enlarged views and form no part of the claimed design.
